UNITED STATES PATENT OFFICE.

LAWRENCE DINKELSPIEL, OF WEST NEW YORK, AND EDWIN BOSSHARDT, OF HUDSON HEIGHTS, NEW JERSEY, ASSIGNORS TO HARNAPP, DINKELSPIEL & CO., INC., A CORPORATION OF NEW YORK.

DESIGN FOR LACE.

Application filed September 23, 1920. Serial No. 412,395. Term of patent 3½ years.

To all whom it may concern:

Be it known that we, LAWRENCE DINKELSPIEL, a citizen of the United States, residing at West New York, in the county of Hudson and State of New Jersey, and EDWIN BOSSHARDT, a citizen of the United States, residing at Hudson Heights, in the county of Bergen and State of New Jersey, have invented a new, original, and ornamental Design for Lace, of which the following is a specification, reference being had to the accompanying drawing, forming part thereof.

The figure is a face view of lace, showing our new design.

We claim:

The ornamental design for lace, as shown

LAWRENCE DINKELSPIEL.

EDWIN BOSSHARDT.
